UNITED STATES PATENT OFFICE.

CHARLES WILLIS KINTER, OF FOLLANSBEE, WEST VIRGINIA.

PICKLING APPARATUS.

Application filed March 5, 1928. Serial No. 259,043.

This invention relates broadly to metal pickling apparatus, and it has for its primary object to provide an improved mechanism whereby the usual pickling racks are reciprocated in the fluid bath contained by the pickling tanks. 5

A further object is to provide an apparatus of the character mentioned embodying means whereby vertical reciprocation of the pickling 10 racks is effected without the employment of guides.

A still further object is to provide, in an improved pickling apparatus, rack carriers, or spider-like supports, having such relatively 15 small dimensions and light weight that transportation thereof to and from their operative positions relative to the pickling tanks is attended with greatly reduced inconvenience and with relatively small danger of injury to 20 the workmen.

With these and other objects in view, the invention resides in the features of construction, combinations of elements and arrangement of parts which will hereinafter be fully described, reference being had to the accompanying drawings, in which—

Figure 1 is a top plan view of the invention;

Figure 2 is a sectional elevation in which 30 the section is taken substantially on line 2—2, Fig. 1;

Figure 3 is a sectional elevation on line 3—3, Fig. 1; and—

Figure 4 is a perspective view of the rack- 35 support or carrier.

Referring to said drawings, 1 and 2 designate companion pickling tanks of rectangular form disposed in spaced parallel relation and containing the pickling fluid, or bath. Located outwardly from and adjacent to the opposite ends of each of the tanks are suitable supports, as concrete pedestals or piers 3, upon which are rigidly mounted heavy upright castings, or brackets, 4, each of which 40 constitutes a support for alined complemental bearings 5 and 6. Journalled in each set of said bearings 5 and 6 are the opposite ends of a short rock shaft 7. Each of the rock shafts 7 located at opposite ends of tank 1 has 45 fixed thereon between the bearings 5 and 6 the middle portion of a walking beam 8, and similar walking beams 9 are fixed on the rock shafts located at the opposite ends of tank 2. 50

Pivottally attached to the opposite ends of 55 each of the walking beams 8 and 9 are the

upper ends of links 10 and 11 by means of which two rectangular frames 12 and 13 are suspended in overhanging relation to the tanks 1 and 2, respectively, said frames being designed as supports for carriers 14 from 60 which are suspended the usual pickling racks 15.

Each of the frames 12 and 13, as herein shown, comprises parallel longitudinally extending side members, each formed of two 65 rigidly attached channel irons 16, and transverse I-beams 17 connecting said side members. Each of said side members carries a trunnion 18 in fixed relation to each of its ends, said trunnions, as herein shown, being 70 formed on the outer end of a block-like insert 19 which is received between and riveted to the adjacent ends of the companion channel irons 16.

For the purpose of providing for alternate 75 vertical reciprocations of the supporting frames 12 and 13, in which reciprocations said frames are at all times maintained in horizontal, or non-tilted, positions, the outer ends of each pair of walking beams 8 and 9 are 80 disposed in suspending relation to the adjacent, or outer, side of the underlying frame, and the inner ends of each pair of said beams occupy like relation to the adjacent, or inner, side of the other, or non-underlying frame. 85 Otherwise expressed, the walking beams 8 have their links 10 disposed in supporting relation to the trunnions 18 which are carried by the outer side member of the frame 12, while the links 11 of said beams 8 support the 90 trunnions carried by the inner side member of the frame 13. Likewise the links 10 and 11 of walking beams 9 carry the trunnions of the outer side member of the frame 13 and the inner side member of the frame 12, respectively. 95

Fixed upon the outer end of each of the rock shafts 7 is a depending crank arm 20, and pivotally attached to and connecting the two crank arms at each of the opposite ends of the machine is an oscillatory member 21, herein shown as of triangular form, but which, obviously, may be of ordinary bell-crank form with the outer ends of its arms pivotally connected to said crank arms, and which, therefore, is hereinafter termed a bell crank. Pivotally connected to the lower, or angular, portion of the bell crank is an end of a horizontal pitman 22 adapted to be reciprocated by any appropriate type of power transmission 100 105 110

means and whereby said crank arms 20 are actuated to swing back and forth for effecting rocking of the walking beams 8 and 9.

Each of the frames 12 and 13 constitutes a support adapted for the reception in overlying seated relation thereto of a portable carrier or spreader 14 of rectangular form and which is preferably fabricated of structural steel, as is best shown in Fig. 4. Said carrier has suitably arranged depending hooks 23 with which are engageable the upper ends of suspension rods 24 upon which is carried the sheet-supporting racks or crates 15. A lifting bail 25 borne by each carrier is designed for receiving in carrying relation thereto the hoisting hook of a crane or other form of mechanical transfer device whereby the racks are transported to and from the pickling tanks. Suitable guide members 26 arranged in pairs are provided in suitable relation on the side members of the frames 12 and 13 whereby the side members of the carriers 14, as the latter are being lowered, are guided to proper seating positions on said frames.

It will be noted that the carriers 14 have such relatively short length that, in effecting transfer to and from their positions over the tanks, the danger of injury to the workmen is much reduced below that which exists in transporting the prevailing long pole-like forms of rack carriers.

As is manifest, operation of the apparatus hereinbefore described effects vertical reciprocation of the rack-carried sheets without the employment of guides or other parts which require frequent repairs or renewals with attendant high cost of upkeep. Further, the structure described provides means whereby pickling of the sheets may be effected with a minimum of agitation of the fluid which constitutes the pickling bath, which is a particularly desirable feature in the production of certain kinds of high-grade sheets.

45 What is claimed is—

1. In pickling apparatus, the combination with companion tanks, of walking beams mounted adjacent to the opposite ends of each tank a supporting frame supported over each tank by said walking beams each frame having its outer side supported by the outer ends of the adjacent beams and its inner side supported by the inner ends of the non-adjacent beams whereby each frame is at all times maintained in horizontal position portable rack-suspension means adapted to seat upon each of said frames and means for rocking said walking beams to effect alternate vertical reciprocation of said frames for elevating and lowering the rack suspension means.

2. In pickling apparatus the combination with companion tanks of walking beams mounted adjacent to the opposite ends of each tank, horizontal supporting frames suspended from said walking beams, one over

each tank, each pair of said walking beams having suspending relation to a side of each of said frames, and means for rocking said walking beams in unison whereby alternate reciprocating vertical movements are imparted to said frames.

3. In pickling apparatus, the combination with companion tanks, a pair of pivoted walking beams associated with each tank, a frame structure over each tank, each pair of walking beams cooperating with the other to support said frame structures in permanently horizontal positions, each pair of said walking beams having suspended relation to an end of each of said frames, means for rocking said beams in unison whereby said frame structures are alternately reciprocated, and portable rack-suspension means removably seated on each of said frame structures.

4. In pickling apparatus, the combination with companion tanks, of companion walking beams associated with each of said tanks, a supporting structure located over each tank, each companion set of walking beams cooperating with the other to suspend each of said supporting structures in permanently horizontal position, each pair of said walking beams having suspended relation to an end of each of said supporting structures, portable rack-suspension means adapted to be removably seated upon each of said supporting structures, and means for rocking said beams in unison for effecting alternate reciprocations of said supporting structures.

5. In pickling apparatus, the combination with companion tanks, of companion walking beams associated with each of said tanks, a supporting structure located over each tank, said supporting structures being supported by an end of each set of said beams for maintaining each of said structures in permanently horizontal position, portable rack-suspension means adapted to be removably mounted on said supporting structures, and means for rocking said beams for reciprocating said supporting structures.

6. In pickling apparatus, the combination with companion tanks, of walking beams mounted adjacent to the opposite ends of each tank, horizontal supporting frames suspended from said walking beams, one over each tank, each pair of said walking beams having suspending relation to a side of each of said frames, and means for rocking said walking beams in unison whereby alternate reciprocating vertical movements are imparted to said frames, said rocking means including a crank arm for each walking beam, and means for simultaneously imparting corresponding oscillating movements to said crank arms.

7. In pickling apparatus, the combination with companion tanks, of walking beams mounted adjacent to the opposite ends of each tank, horizontal supporting frames sus-

pended from said walking beams, one over each tank, each pair of said walking beams having suspending relation to a side of each of said frames, and means for rocking said walking beams in unison whereby alternate reciprocating vertical movements are imparted to said frames, said rocking means including a crank arm for each walking beam, a horizontally reciprocable pitman at each of the opposite ends of the tanks, and means pivotally connecting each pitman to each of the adjacent crank arms.

8. In pickling apparatus, the combination with companion tanks, of companion walking beams associated with each of said tanks, a supporting structure located over each tank, said supporting structures being suspended from said walking beams by means of pivoted links, each set of companion beams having suspending relation to a side of each supporting structure whereby each of said structures is maintained constantly in horizontal position, portable rack-suspension means for mounting on said structures, and means for rocking said walking beams for effecting alternate vertical reciprocations of said structures and the thereby-carried suspension means.

9. In pickling apparatus, the combination with companion tanks, of walking beams mounted adjacent to the opposite ends of each tank, horizontal supporting frames suspended from said walking beams, one over each tank, the walking beams of each pair having their outer ends occupying suspend-

ing relation to the outer side of the adjacent frame and their opposite ends occupying like relation to the inner side of the other frame, whereby said frames are constantly maintained in horizontal positions, portable rack-suspension means adapted to be removably mounted on each of said frames, and means whereby said walking beams are actuated in unison for lowering and elevating said frames.

10. In pickling apparatus, the combination with companion tanks, of walking beams mounted adjacent to the opposite ends of each tank, horizontal supporting frames suspended from said walking beams, one over each tank, the walking beams of each pair having their outer ends occupying suspending relation to the outer side of the adjacent frame and their opposite ends occupying like relation to the inner side of the other frame, whereby said frames are constantly maintained in horizontal positions, portable rack-suspension means adapted to be removably mounted on each of said frames, and means whereby said walking beams are actuated in unison for lowering and elevating said frames, said actuating means including a crank arm associated with each walking beam, bell crank levers connecting adjacent crank arms, and a horizontally reciprocable pitman having connection with each of said levers.

In testimony whereof, I affix my signature.

CHARLES WILLIS KINTER.
